UNITED STATES PATENT OFFICE.

ARTHUR C. GLOVER, OF IPSWICH, AND WILLIAM E. HADLOCK, OF WENHAM, MASSACHUSETTS.

COMPASS-LIGHT.

No. 842,092.

Specification of Letters Patent.

Patented Jan. 22, 1907.

Application filed May 28, 1906. Serial No. 319,163.

To all whom it may concern:

Be it known that we, ARTHUR C. GLOVER, residing in Ipswich, and WILLIAM E. HADLOCK, residing in Wenham, county of Essex, and State of Massachusetts, citizens of the United States, have invented an Improvement in Compass-Lights, of which the following description, in connection with the accompanying drawings, is a specification, like letters on the drawings representing like parts.

The present invention relates to a compass-light, and is embodied in the combination, with the compass, of any kind of an electric light contained in an inclosing case mounted on the compass-frame and provided with a shutter so arranged as to direct the rays of light to any desired point of the compass and at the same time to shut off the light entirely, if desired.

The invention is shown as applied to a ship's compass of the usual type mounted on gimbals, the entire arrangement forming what is known as a "binnacle."

Figure 1 is a front elevation of a compass-light embodying the invention, and Fig. 2 is a transverse vertical section on the line x^2 of Fig. 1.

As herein shown, the compass A is mounted in the gimbal-frame A^2 at the top of a casing A^3 . Secured to the upper portion of the compass A is an inclosing case a , which contains an electric lamp b , which is capable of giving sufficient light to easily read the compass at a given point.

The casing a is provided with a supporting member a^2 , shown as secured by means of one or more screws a^3 to the outer edge of the compass A, the said casing being of opaque material and entirely inclosed, except for an opening a^4 near the lower part of the casing, the said opening being over the compass-dial. This opening is of sufficient width to shed light over a considerable portion of the dial, but is combined with a shutter a^5 , provided with a smaller opening a^6 , whereby a smaller area of light can be directed to various points of the dial. In the construction shown the shutter a^5 consists of a sleeve pro-

vided with a handle a^7 , having a guide projection a^8 , which travels in a slot a^9 , formed in the wall of the casing, so that by rotating the said sleeve the position of the opening a^6 will be varied, so as to throw the light from the middle toward the edge of the dial, and vice versa. The travel of the sleeve is sufficient, as indicated in dotted lines, Fig. 2, to carry the opening a^6 entirely beyond the edge of the opening a^4 , so as to shut off the light completely, if desired.

By the construction described it will be seen that a substantially steady light can be maintained at a certain point on the compass-dial regardless of the position of said dial with relation to the fixed frame in which the compass is supported, the said light being directed to and centered upon that part of the dial which is to be observed without illuminating other parts of the dial, the casing constituting a shade for the eyes of the observer, so that the compass may be very easily read.

We claim—

1. The combination with the compass mounted on gimbals; of a casing supported upon the said compass; an electric lamp inclosed in said casing; and an opening through the wall of said casing to permit the light to fall upon the compass-dial, substantially as described.

2. The combination with a compass; of an opaque casing mounted on the compass above the dial; an electric lamp contained in said casing; an opening through the wall of said casing adjacent to the compass-dial; a shutter provided with a smaller registering opening and movable with relation to the main opening in the casing, substantially as and for the purpose described.

In testimony whereof we have signed our names to this specification in the presence of two subscribing witnesses.

ARTHUR C. GLOVER.
WILLIAM E. HADLOCK.
